UNITED STATES PATENT OFFICE

OTTO J. MOEHLER, OF BLOOMFIELD, NEW JERSEY, ASSIGNOR TO GENERAL ELECTRIC VAPOR LAMP COMPANY, OF HOBOKEN, NEW JERSEY, A CORPORATION OF NEW JERSEY

DESIGN FOR A COMBINED SUPPORT AND HOUSING FOR AN ELECTRIC DISCHARGE DEVICE

Application filed September 25, 1929. Serial No. 32,862. Term of patent 14 years.

To all whom it may concern:

Be it known that I, OTTO J. MOEHLER, a citizen of the United States, residing at No. 61 Yanticaw Avenue, Bloomfield, in the county of Essex and the State of New Jersey, have invented a new, original, and ornamental Design for a Combined Support and Housing for an Electric Discharge Device, of which the following is a specification, reference being had to the accompanying drawing, forming a part thereof.

The figure is a perspective view of a support and housing showing my new design.

The new design is substantially the same on the opposite side thereof as on that side shown in the drawing.

I claim:

The ornamental design for a combined support and housing for an electric discharge device substantially as shown and described.

OTTO J. MOEHLER.
